UNITED STATES PATENT OFFICE.

FRANK HALL, OF DULUTH, MINNESOTA, ASSIGNOR OF ONE-HALF TO CLARA ELFSTRAND, OF SANDSTONE, MINNESOTA.

DESIGN FOR A BABY-CARRIAGE.

SPECIFICATION forming part of Design No. 30,190, dated February 14, 1899.

Application filed December 30, 1898. Serial No. 700,766. Term of patent 7 years.

To all whom it may concern:

Be it known that I, FRANK HALL, a citizen of the United States, residing in the city of Duluth, county of St. Louis, State of Minnesota, have invented and produced a new and original Design for Baby-Carriages, of which the following is a specification, reference being had to the accompanying drawings, wherein—

Figure 1 is a side elevation, and Fig. 2 a rear elevation, of a baby-carriage embodying my design.

By reference to said drawings it will be seen that the entire carriage, with the exception of the brackets or hangers which connect the wheel-axles to the body of the carriage, is made up of wire, so disposed as to give to the carriage a unique and ornamental appearance. The longitudinal and cross wires of the body are interlocked by winding wires of smaller cross-section to space the same apart the proper distances and hold the same together in the proper relation to each other to produce the carriage-body. The marginal longitudinal wire of the body-bottom is wound with a wire of smaller cross-section for its entire length to produce a bead-like effect. The second and third longitudinal wires from the top in the side walls of the body are similarly wound for the same purpose. The top wire of the body is wound with a coiled-wire spring closely compressed, thereby producing a rim having the appearance or effect of rope braid. To the body in that portion thereof surrounding the highest part of the same directly under the braided rim is attached a wire wound with a wire of smaller cross-section in such manner as to produce the appearance or effect of a loop braid.

To the bottom of the body are secured the horizontal ends of a bail-like handle, the vertical section of which bail has its stems also secured to the back of the body and wound with a wire of smaller cross-section, so as to have the appearance or effect of a coiled-wire handle.

The wheels are made up of wire rings wound with a wire of smaller cross-section to afford the tire and continued in radial direction to afford the spokes, and then in a horizontal direction to afford the core of the axle connecting the two wheels. Each core is then wound by a wire of smaller cross-section to complete the axle and wheel-hubs and hold the other parts of the wheel in the proper position with respect to each other. The wheels and axles so formed have the appearance or effect of being made of coiled wire in respect to their rims and axles.

The carriage thus formed has a unique and attractive appearance, wherein the coiled and braided wire effects are the prominent and essential features of the design.

The carriage embodying this design is primarily intended as a toy carriage for young children, but may be readily made of sufficient strength for actual service in the customary way.

Having described my invention, what I claim as new, and desire to secure by Letters Patent of the United States, is—

The design for a baby-carriage, substantially as herein shown and described.

FRANK HALL.

In presence of—
H. C. NELSON,
C. CARLSON.
